United States Patent Office

Des. 196,190
Patented Sept. 3, 1963

196,190

COFFEE POT OR SIMILAR ARTICLE

Howard Treu, Greenville, Conn., assignor to The Block
China Company, New York, N.Y., a firm

Filed Feb. 11, 1963, Ser. No. 73,541

Term of patent 7 years

(Cl. D44—26)

FIG. 1 is a plan view of a coffee pot or similar article showing my new design.

FIG. 2 is a front view with parts in section.

FIG. 3 is a left side elevational view;

FIG. 4 is a right side elevational view.

I claim:

The ornamental design for a coffee pot or similar article, as shown.
